UNITED STATES PATENT OFFICE.

HENRY CLAUSEN, OF SAN FRANCISCO, CALIFORNIA.

VEHICLE-WINDOW DEVICE.

1,424,282.

Specification of Letters Patent. Patented Aug. 1, 1922.

Application filed September 28, 1921. Serial No. 503,814.

To all whom it may concern:

Be it known that I, HENRY CLAUSEN, a citizen of the United States, and resident of the city and county of San Francisco, State 5 of California, have invented new and useful Improvements in Vehicle-Window Devices, of which the following is a specification.

My invention has for its object means for clamping the sliding windows in automobiles 10 or the like, wherebv when the windows have been moved into a desired position they may be clamped to prevent rattling or further movement during the motion of the vehicle.

By referring to the accompanying drawings my invention will be made clear.

Fig. 1 is a cross section through a pair of windows and the upper portion of a stationary frame of the body of any well known vehicle, taken on the line I—I of Fig. 2, details of other portions of which vehicle are not shown but well known.

Fig. 2 is a plan view of Fig. 1 with the windows and cover plate removed.

Fig. 3 is a detail in perspective of the 25 double link and fulcrum screw.

Fig. 4 is a perspective view of two of the side plates in their relative position.

Fig. 5 is the base plate, in perspective.

Fig. 6 is a plan of the cover plate adapted 30 to set over the mechanism shown assembled in Fig. 2.

Fig. 7 is an end view of the plate of Fig. 6.

Fig. 8 is a section through Fig. 9 on the line VIII—VIII thereof and shows a variation 35 in the cover plate and manner of tracking of the sash.

Fig. 9 is a fragmentary side view of either Figs. 1 or 8.

Throughout the figures similar numerals 40 refer to identical parts.

A portion of the assembled body is shown by the numeral 1. This is preferably chambered out at 2, and at 3, 4, are shown a pair of sliding sash which may be normally guided upon the track 5 or which may be individually tracked as shown at 6 and 7 of Fig. 8. At 9 is a base plate mounted rigid with the body 1. Mounted upon the base plate are a pair of sliding members guided on the 50 edges 10, 11. The members have vertical segments 12, 13, respectively, which are adapted to clamp against the sides of the windows

3 and 4, respectively. These sides 12 and 13 are shown in their extended position in Fig. 2 at which time the windows may be freely moved therebetween, whereas in Fig. 1 they are shown in their clamped position at which time the windows 3, 4, are held rigidly against any rattling or movement between the said segments. At 14 is a lug extending 60 downward from the plate member 10, which lug is in threaded engagement with the screw 15. This latter is adapted to rotate by the milled head 26 but held against endwise movement in the body 1. The double link of 65 Fig. 3 engages a pin 16 on the plate 10 and a pin 17 on the plate 11, and at 18 the link is mounted on a fulcrum 20 carried on the base plate 9. The several parts above enumerated are set in the body 1 to a sufficient depth 70 so that the plate 19 when fitted over the parts obscures and protects them, and by the screws as 20 the parts are securely held to the body 1. The surface of the plate 19 at such time being flush with the remaining 75 track portion 21 of the vehicle body the windows may slide freely thereover. It will now be seen that when the windows are moved into the position shown in Fig. 9 they may be readily and simultaneously clamped 80 or unclamped at the will of the operator by the single movement of the milled head screw 26.

I claim:

1. As an article of manufacture, a clamping device for a pair of windows comprising a body portion and a pair of angle clips, one adapted to clamp one and the other adapted to clamp the other of said windows, tracking means on said plate by which said clips 85 are constrained to move parallel to each other and at right angles to said windows, a lower member pivoted at its center to said body plate and at each end pivoted to one of said angle clips, a screw member rotatably 90 mounted against end-movement, said screw engaging one of said clips whereby said angle clips are movable toward or away from each other.

2. An article of manufacture as set forth 100 in claim 1 and central guide means for said windows on said body portion.

HENRY CLAUSEN.
